UNITED STATES PATENT OFFICE.

JOHN L. MEADOWS, OF HUME, ILLINOIS.

COLLAPSIBLE HOUSE.

Application filed May 11, 1923. Serial No. 638,828.

To all whom it may concern:

Be it known that I, JOHN L. MEADOWS, a citizen of the United States, resident of Hume, in the county of Edgar and State of

Illinois, have made a certain new and useful invention in Collapsible Houses; and I declare the following to be a full, clear, and exact description of the same, such as will enable others skilled in the art to which it

10 appertains to make and use the invention, reference being had to the accompanying drawings, and to letters or figures of reference marked thereon, which form a part of this specification.

15 Figure 1 is a perspective view of the invention.

Figure 2 is a transverse vertical section of the same.

20 Figure 3 is a central longitudinal vertical section of the same, partly broken away.

Figure 4 is a detail perspective view of the top section.

Figure 5 is a similar view of a roof section.

25 Figure 6 is a similar view of a side section.

Figure 7 is a similar view of an end section.

30 Figure 8 is a detail fragmentary sectional view of a corner of the coop, showing the joint.

Figure 9 is a similar view showing a modification.

35 Figure 10 is a similar view showing a further modification.

Figure 11 is a similar view showing a further modification.

40 Figure 12 is an end view partly in transverse section showing a modification of the coop.

Figure 13 is a vertical central longitudinal section of the same, partly broken away.

Figure 14 is a perspective view of the coop taken apart and parts stacked together.

45 The invention has relation to poultry coops of collapsible houses or kennels, especially adapted to be made of wood, and for use with poultry, dogs, hogs, and the like, or for use as a garage in a larger structure, an object being to provide an improved house of this description, which may

50 be readily put together or taken down by an unskilled person, which is easily opened for cleaning and airing, is rain and weather-proof, well ventilated, of simple construction and capable of economical manufacture.

Other objects and advantages will herein-after appear.

The invention consists in the novel construction and combination of parts, as hereinafter set forth.

In the accompanying drawings illustrating the invention, the numeral 1 designates opposite rectangular sides, and 2 opposite ends having each a tapered top portion 2^a, 65 said sides and ends having detachable corner connection with each other, the material used being preferably wood, and marginal grooves 3 being formed in one of said parts and engaged by the adjacent edge portion of 70 the other part in making the connection, it being preferred to have the joint of dovetailed nature or other lock joint form, as shown in Figures 8 and 9 of the drawings, in order that when the opposite sides and 75 ends are connected up or slid together, these parts will remain connected up in box form.

The sides 1 of the coop are provided at their lower edges with inward projecting flanges or cleats 4, whereon rests the bottom 5 of the coop, these cleats or flanges projecting at their outer ends at 6, beyond said bottom, and the ends 2 of the coop resting upon said projections 6.

Resting upon the inclined top edges 2^b of 85 the coop ends and projecting over the sides 1, are the roof sections 7, each of rectangular form and having lower cleats 8, fitting within said ends, and at their lower ends abutting against the coop sides 1 to limit 90 the downward movement, and abutting also against the coop ends to limit the endwise movement, the abutment against the coop sides being through the medium of vertical cleats 9, carried by said sides and forming 95 an element of the lock joint shown in Figure 8, said vertical cleats having upper notches 10, with which the lower beveled ends 8^a of said cleats engage, as shown in Figure 2.

The roof sections 7 are spaced apart at 100 their upper ends by an interval 7^b, and fitting thereover and closing said interval is a longitudinal top section 11, the ends 12 of which have a lapping engagement with the upper edge portions of said end sections as shown 105 in Figure 2, the engaging parts being reduced to bring them into the same plane, and a hook connection 13 being provided at each end to hold the top section and the end sections together.

110 The top section 11 has parallel sides 14, spaced apart to accord with the aforesaid

interval 7^a, and provided with ventilation holes 14^a, the interval between said sides being in communication with the interior of the coop and thereby, in connection with 5 lower air holes 15 in the coop sides, providing for good ventilation. The top section has its sides 14 beveled at their lower edges at 16 and resting upon the upper portions 7^a of the roof sections.

10 If desired, the cleats 4 may have ridges 4^a, with which grooves 5^a of the coop bottom may engage, as shown in Figure 2.

The coop being crated, and it being desired to lift it from the crate, the top section 15 being lifted, will lift the coop ends owing to hook connections 13, and will lift the roof sections and the coop sides, owing to engagement of cleats 8 with the notches of cleats 9, as stated.

20 The coop rests upon the longitudinal cleats 4 of the sides 1, whereby the bottom 5 is raised from the ground. The coop ends 2 resting upon the cleat extensions 6 and having corner connection with the coop sides 25 1, will prevent displacement of said ends relative to said sides, and hold the ends and sides in box form. This construction also facilitates lifting the bottom 5 between said ends and sides without disturbing the box 30 formation of said ends and sides.

A modification of the invention is shown in Figures 13 and 14, wherein the coop ends 2 are provided upon their inner sides with central vertical cleats 18, extending upwardly above said ends at 18^a, the top section having its ends located outside said extensions 17^a and in the same plane as the coop ends, with which they have hook connection 13^a.

40 This coop has interchangeable ends, sides, top sections, roof sections and floor or bottom section, and slides apart and stacks together in a very small space, no tools being required to set the coop up or take it down.

45 The construction being preferably of wood, is cool in summer, warm in winter and being made of white pine is very durable.

The coop is easily cleaned, is well ventilated, rain and weather proof. In cleaning, the roof sections or top boards are slid out of their seats, or slid upwardly slightly to release the lock engagement of cleats 8 and 9, and removed, the top section 11 being first 50 removed. One of the roof sections may be removed if desired to let the hen in and out and keep the chicks on the wood floor of the coop. The lock joint construction enables two hooks 13 to hold the entire coop 55 together. Glass or other transparent insertions 19 may be provided in the roof sections 7.

In Figure 10 of the drawings a modification of the corner connection of the sides 60 and ends of the coop is shown, wherein the

joint is not of lock form, but is provided with a hook 19, to hold the parts together.

In the modification of the invention shown in Figures 12 and 13, hook connection 13^b of the ends and bottom of the coop is desirable, to facilitate the lifting of the coop as a whole.

I claim:—

1. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box formation with said bottom removed therefrom.

2. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting upon said tapered upper portions and spaced apart at their upper ends, and a longitudinal top section having spaced sides resting upon the upper edges of said roof sections, and having ends provided with detachable hook connection with the coop ends.

3. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting thereon and having cleats, the opposite sides having end notches and said last named cleats having tapered lower ends engaging said notches, and a longitudinal top section resting upon the upper edges of the roof sections and having detachable hook connections with the opposite ends.

4. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting upon said tapered upper portions and spaced

- apart at their upper ends, and a longitudinal top section having spaced sides resting upon the upper ends of the roof sections and having ends provided with detachable connections with said opposite ends, said opposite sides having end notches and said roof sections having cleats having tapered lower ends engaging said notches.
5. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, and inclined roof sections resting thereon and having cleats abutting at their lower ends against said opposite sides and laterally against said opposite ends.
10. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting thereon, and a longitudinal top section connecting said ends and lapping over said roof sections.
15. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting thereon, and a longitudinal top section connecting said ends and lapping over said roof sections.
20. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting thereon, and a longitudinal top section connecting said ends and lapping over said roof sections.
25. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting thereon, and a longitudinal top section connecting said ends and lapping over said roof sections.
6. In a collapsible house, opposite sides having lower cleats, a bottom resting upon said cleats, the cleats projecting endwise beyond said bottom, and opposite ends having corner joint connection with said sides and resting upon the ends of said cleats, said corner joint connection being adapted to hold said opposite ends and sides in box form with said bottom removed therefrom, said opposite ends having tapered upper portions, inclined roof sections resting thereon, and a longitudinal top section connecting said ends and lapping over said roof sections.

In testimony whereof I affix my signature.

JOHN L. MEADOWS.
